UNITED STATES PATENT OFFICE.

JOHN C. REDINGTON, OF QUINCY, ILLINOIS, ASSIGNOR TO DU-PLEX ENVELOPE CORPORATION, OF QUINCY, ILLINOIS, A CORPORATION OF ILLINOIS.

DUPLEX MAILING ENVELOPE.

Application filed December 24, 1923. Serial No. 682,373.

To all whom it may concern:

Be it known that I, JOHN C. REDINGTON, a citizen of the United States, and resident of Quincy, Adams County, Illinois, have invented a certain new and useful Improvement in Duplex Mailing Envelopes, of which the following is a specification.

This invention relates to duplex envelopes of the kind in which a relatively small compartment is provided within the area of the relatively large compartment formed by the body of the envelope itself, whereby first class mail, or other mail matter, can be placed in the smaller compartment, and sealed if desired, while second or third or fourth class, or other mail matter, can be placed in the larger compartment and left open or accessible to inspection while being transmitted through the mails.

Generally stated, the object of the invention is to provide a novel and improved construction whereby a duplex envelope having a plurality of compartments may be constructed in a simple and satisfactory manner, in a way that will be calculated to insure attracting the attention of the person who receives the envelope, and in a way that will tend to render the envelope more satisfactory.

It is also an object to provide certain details and features of construction tending to increase the general efficiency and the desirability of a duplex envelope of this particular character.

To the foregoing and other useful ends, the invention consists in the matters herein-after set forth and claimed, and shown in the accompanying drawings, in which,—

Fig. 1 is a front elevation or face view of a duplex envelope embodying the principles of the invention.

Fig. 2 is a vertical, transverse section on line 2—2 in Fig. 1.

Fig. 3 is a horizontal section on line 3—3 in Fig. 1.

Fig. 4 is a plan view, on a smaller scale, showing the inner surface of the blank from which the body of the duplex envelope is made.

Fig. 5 is a similar view, showing the blank which forms the inner wall of the smaller compartment of the duplex envelope.

As thus illustrated, the invention comprises a rectangular envelope body formed from the blank shown in Fig. 4, having the

front wall 1 with a curved or irregular slit 2 therein, extending vertically, and having an opening 3 to expose the address on the letter. The flaps 4 and 5 are folded over and fastened together, at the back of the envelope, as shown at 6, by the gum or mucilage 7 on the flap 4, in a manner that will be readily understood. The end flap 8 is preferably gummed at 9 to fold over and seal this end of the envelope. The other end of the blank has a wide flap 10, which is preferably not adapted to be sealed, inasmuch as it is merely tucked inside of the envelope after the second or third, or fourth class, or other mail matter, has been placed in the relatively large compartment 11 thus formed. The smaller compartment 12 is formed by the blank shown in Fig. 5, comprising a rectangular sheet of paper 13 gummed around its edges at 14 to adhere to the inner surface of the front wall 1 of the main envelope. The slit or incision 2 forms a flap 15, in effect, and the other surface of the sheet 13 can be gummed to fasten it to this flap, and in addition, if so desired, a strip of adhesive paper tape 16 can be applied as shown to the inner surface of the envelope to fasten the end of the sheet 13 in place. This end of the sheet 13 has a wide flap 17, which is gummed at 18 to enable it to be folded over and sealed on the outer surface of the envelope, as indicated in Fig. 1, thus sealing the smaller compartment. A sheet of transparent material 19 is preferably applied to the inner surface of the smaller compartment to close the opening 3 in the well known manner. Thus the flaps 10 and 17 are adjacent each other, so that the two compartments are both open at the right-hand end thereof, before the envelope is closed or before the smaller compartment is sealed, and whereby both compartments are opened at the right-hand end of the envelope as a whole. Of course, the two flaps 10 and 17 can be at either end of the envelope, depending upon circumstances and requirements, without departing from the spirit of the invention. By associating the two flaps together certain advantages are obtained in the manufacture and use of envelopes of this kind.

The flap 17 is of sufficient length or width, as shown, to extend quite close to the end edge 20 of the envelope, and before the envelope is used the flap 17 extends as shown

in dotted lines in Fig. 1, so that the exposed edge 21 is some distance from the fold line 22 of the flap 17, thus facilitating the insertion of the letter or other mail matter into the smaller compartment. After things have been inserted in both compartments, and after the flap 10 has been tucked inside, a number of these envelopes can be laid one upon the other, in a row, with the edge 20 of each envelope disposed somewhere between the line 22 and the line 23, so that the gum or mucilage 18 will be exposed, and with the ends of the flaps 17 of the different envelopes slightly raised. With the envelopes laid out in this way on a table, for sealing the smaller compartments, it will be found that the edge 24 of the flap 17 is so close to the edge 20 of the envelope that very little of the surface of the envelope is exposed between these two edges, and consequently a wet sponge, roller, or other device can be passed over the series of envelopes, without touching anything more than the gummed surfaces 18 of the flaps 17, inasmuch as practically all other surfaces will be covered, and the small portion of the front wall 1 of each envelope which remains exposed or uncovered will be just enough below the raised edge 24 of each flap to prevent the sponge or roller, or other device, from wetting the surface of the envelope itself. Then the envelopes are separated and the flaps 17 are folded over and secured in place, as shown in Fig. 1, and by applying separate postage to the larger and smaller compartments, as indicated at 25 and 26, the duplex envelope will be ready for the mails. A line or border 27 serves to outline the smaller compartment on the face of the envelope, and tends to call attention to the fact that the envelope contains something more than merely the second or third, or fourth rate, mail matter enclosed in the larger compartment.

In assembling the two blanks, both flaps 10 and 17 will extend in the same direction, regardless of whether the flaps are at one end or the other of the envelope. The flap 17 is desirably of such size and relative arrangement that several of the envelopes can be laid out upon a table, overlapping each other, in the manner explained, for the purpose of dampening the gum 18 by a sponge or roller, or other device, in the manner explained, without danger of wetting the front surface of the envelope. The flaps 17 are of such size that each of these flaps may be partially covered by the end of the next envelope, as the flap 17 is of such size that the entire surface thereof does not have to be gummed or provided with an adhesive, and thus the distance between the edges 20 of the series of envelopes is reduced practically to a minimum. To still further reduce this exposed area of the front surface

of the envelope, it is obvious that the flap 17 can be made larger and of such size and shape that its edge 24 will coincide with the edge 20 when the flap is in position for the wiping operation. Or, on the other hand, the slit 2 can be quite close to the edge 20, or so close that its upper and lower ends fall on this line 20, and in that event the flap 17 will extend beyond the edge 20 when this flap is in position for the wiping operation. In other words, some space can be left between the lines 20 and 24, and consequently between the flaps 17 of the different envelopes, when they are in position for the wiping operation. On the other hand, if desired, this slight space can be eliminated entirely by so proportioning the different parts that the end of each flap 17 will reach to the line 22 of the next flap, in the manner explained.

The invention contemplates, therefore, the arrangement or proportioning of the flaps 17 of the different envelopes of this kind, as explained, in such a manner that, when they are laid one upon another, in a row, upon a table, they can be treated with a sponge or roller, or other wiping device, to moisten the gum 18 without danger of seriously wetting the front surface of any of the envelopes. In such position the edge 24 of each flap is nearer the edge 20 (and also nearer the entrance to the larger compartment) than the entrance 21 of the smaller compartment.

The front or face of the envelope, of course, is the side upon which the address is applied, irrespective of construction. As shown, the wall 1 is used as the front or face of the envelope, while the flaps 4 and 5 are used to form the back of the envelope, for the simple reason that the address appears through the opening 3, or in any suitable manner, on the side of the envelope formed by the wall 4 of the blank.

Thus the envelopes are filled and wiped and closed and stamped without turning them around. In other words, the envelopes keep the position shown in Fig. 1 for all of these operations, for the envelopes are arranged lengthwise in a row, in their overlapping relation, and the wiping with a sponge or other means for dampening the mucilage is lengthwise of each envelope. Therefore, the envelope is filled, in both compartments thereof, while keeping the normal position shown in Fig. 1, and the envelopes are then arranged in position for wiping, without turning them around, and the mucilage is moistened, and the envelopes are thereafter closed and stamped while in this same position, all of which expedites and renders more satisfactory the use of a duplex envelope of this general character. The flap 17 is of substantial length, it will be seen, so that it extends close to the edge 130

20 of the main envelope, or substantially so, and here will be very little if any of the face of each main envelope exposed to contact with the sponge or other moistening means, when the envelopes are laid out lengthwise and wiped in the manner explained. In addition, the flap 17 of each envelope is down in the lower right hand corner, where it is convenient to perform the various operations, including the wiping of the flaps to moisten the mucilage, by a sponge or other means held in one hand, while the other hand presses on the upper portion of the envelopes to hold them down in place. For example, when the envelopes are laid out in a row, the left hand is pressed on the envelopes above the row of protruding flaps, and thus above the line of wiping motion, while the other hand with the sponge or other moistening means is moved along the row of flaps to moisten the mucilage thereon.

The smaller compartment is of considerably less area than the larger compartment, so that there is a substantial area at one side, preferably the upper side, of the row of flaps 17 formed by arranging the envelopes as explained. The left hand can be pressed down upon this area at one side of the row of smaller compartments, to hold the envelopes in place, when they are laid out in a row, so that they can be held by one hand while the wiping operation is performed with the other hand. Thus one hand is pressed down on the envelopes, at one side of the line of wiping motion, so that one hand does not interfere with the other. In addition, it will be seen that the wiping motion is parallel with the addresses of the envelopes. Thus the envelopes do not have to be turned around when they are arranged for wiping, but are simply laid out with their addresses parallel with the row of overlapping envelopes. Thus the envelopes are filled and wiped and closed and stamped without turning them around—that is to say, while they face upwardly in reading position.

Thus the flap 17 is much larger than is necessary merely for sealing purposes, and is of such size and location that it extends close to the edge 20 when bent back into the position shown in dotted lines in Fig. 1, and is of such size that when it occupies the position shown in dotted lines in Fig. 3, is in position to be moistened by the wiping motion over the row of flaps, as the flaps will be in raised position, to some extent, thus permitting a long row of these flaps to be moistened by one wiping motion, which motion is not obstructed or interfered with by any pressure exerted on the upper portions of the envelopes to hold them in place during this operation. The enlargement of the flap 17 is to cover and

protect some of the front of the envelopes, and to allow these flaps to extend upwardly in position for wiping. The smaller compartment is formed against the inner surface of the front wall of the larger compartment, so that the flap 17 is sealed directly against the front wall of the larger compartment, which wall is the seamless front wall of the envelope itself. As the flap 17 is of some length, and thereby extends quite a distance toward the edge 20, and an equal distance from the edge 22 in the opposite direction, the place for the address is shifted or displaced a little, or any suitable distance, toward the left, as shown so as not to be covered by the flap 17 when the latter is folded over and sealed down upon the face or address side of the envelope.

What I claim as my invention is:

1. That improvement in duplex envelopes which contemplates sufficient enlargement and special formation and location of the small compartment sealing flaps thereof, when a plurality of such envelopes are arranged in a row in overlapping relation to permit moistening thereof by wiping a sponge over the row of flaps, comprising means forming a plurality of compartments, one of said compartments being relatively small and within the area of the larger compartment, the smaller compartment being formed upon the inner surface of the front wall of the larger compartment, and a sealing flap of substantial length on the face of the envelope for the smaller compartment, which flap is of sufficient size and location to extend close enough to the edge of the envelope to permit several envelopes of this kind to be arranged in overlapping relation with the adhesive sides of their sealing flaps exposed and facing upward, and with the back or non-adhesive side of each flap facing downward but raised a distance from the address side of its allotted envelope, so that the free edge of each flap is nearer the edge of its envelope than the entrance to the smaller compartment, whereby the flaps which are larger than is necessary for merely sealing purposes may all extend in the same direction in said row and in sufficiently raised position for wiping lengthwise of the envelopes and parallel with the addresses thereof to moisten the adhesive sides of the flaps, by means held in one hand while the other hand is pressed down on the envelopes at one side of the line of wiping motion, with the flaps thereby close together to minimize the wetting of the front surface of the envelopes during the operation of wiping the said flaps thereof, the envelopes presenting a substantial area forming a wide margin at one side of said row of flaps, upon which to exert pressure to hold

- the envelopes down while wiping the flaps, thereby preventing any obstruction to or interference with the wiping motion, and whereby the envelopes are filled and wiped 5 and closed and stamped without turning them around, each flap when sealed adhering directly to said front wall of the larger compartment, which is the front wall of the envelope itself.
- 10 2. A structure as specified in claim 1, said flap having a fold line which is parallel with one end edge of the envelope so that said fold line is vertically disposed when the envelope is viewed from the front, and 15 the larger compartment having a flap which folds along a line coincident with said end edge of the envelope, whereby both flaps project in the same direction before folding, but with the two flaps facing in opposite directions and whereby the two flaps both extend in the opposite direction after the folding thereof.
3. A structure as specified in claim 1, the front wall of said envelope having a slit or incision therein of a shape to form a flap, 25 and the smaller compartment being formed by a sheet fastened to the outer surface of this flap.
4. A structure as specified in claim 1, said envelope having a flap for accessibly closing 30 the larger compartment, both flaps extending in the same direction before being folded and both flaps extending in the same direction after the folding thereof, and the two flaps being adjacent each other, substantially as and for the purpose described 35
5. A structure as specified in claim 1, said flap being integral with a section of sheet material which forms the inner wall of the smaller compartment, and means to fasten 40 this section of sheet material to a portion of the outer surface of the front wall of the envelope.

JOHN C. REDINGTON.
